No. 745,147.

Patented November 24, 1903.

UNITED STATES PATENT OFFICE.

JAMES I. BROUGHTON, OF WALKERVILLE, MONTANA.

BOILER COMPOUND.

SPECIFICATION forming part of Letters Patent No. 745,147, dated November 24, 1903.

Application filed September 14, 1903. Serial No. 173,145. (No specimens.)

To all whom it may concern:

Be it known that I, JAMES I. BROUGHTON, a citizen of the United States, residing at Walkerville, in the county of Silverbow and State of Montana, have invented certain new and useful Improvements in Boiler Compounds; and I do declare the following to be a full, clear, and exact description of the invention, such as will enable others skilled in the art to which it appertains to make and use the same.

My invention is an improved boiler compound for use in preventing scaling in steam-boilers in which alkali-water is employed; and it consists in the compound of potatoes, linseed-meal, tallow, and black oil, as hereinafter described.

My improved compound is a mixture of potatoes, (finely ground,) seventy-five pounds; linseed-meal, fourteen pounds; tallow, twelve

pounds; black oil, (crude petroleum), one and one-half gallons.

About eight pounds of this compound should be put every twenty-four hours in a two-hundred-and-fifty-horse power steam-boiler.

My improved compound retards scaling and effects a considerable economy in fuel and in lubricating-oil.

Having thus described my invention, I claim—

A boiler compound consisting of potatoes, linseed-meal, tallow and black oil, substantially in the proportions described.

In testimony whereof I have hereunto set my hand in presence of two subscribing witnesses.

JAMES I. BROUGHTON.

Witnesses:

JAMES PRATO,
JOHN GHELLO.
